UNITED STATES PATENT OFFICE.

LOOMIS N. McFALL, OF DENVER, COLORADO.

GRINDING ATTACHMENT FOR SEWING-MACHINES.

1,391,555.

Specification of Letters Patent. Patented Sept. 20, 1921.

Application filed January 20, 1919. Serial No. 271,967.

To all whom it may concern:

Be it known that I, LOOMIS N. McFALL, a citizen of the United States, residing at the city and county of Denver and State of Colorado, have invented certain new and useful Improvements in Grinding Attachments for Sewing-Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means adapted to be attached to the fly-wheel of the sewing machine, whereby grinding of various kinds, as may be required in any household, may be accomplished. This attachment includes a frame, preferably of cone-shape, whose larger extremity or base is detachably connected with the fly-wheel of the machine, the structure extending outwardly beyond the fly-wheel and carrying a stem upon which may be secured an emery wheel or other grinding member, the same emery wheel or grinding device being itself readily detachable from the stem, whereby grinding members of different quality may be employed, as circumstances may require.

It is intended to use the grinding attachment when the driving mechanism of the machine is disconnected from the sewing mechanism, or that which operates the needle. In other words, the machine is adjusted so that the sewing mechanism is not operated but the driving structure is still connected to rotate the fly-wheel, as will be readily understood by those familiar with the structure and operation of sewing machines.

Having briefly outlined my improvement, as well as the function it is intended to perform, I will proceed to describe the same in detail, reference being made to the accompanying drawing, in which is illustrated an embodiment thereof. In this drawing:

Figure 1 is a fragmentary front elevation of a sewing machine, showing my improvement applied to the fly-wheel, thereof, and in position for use.

Fig. 2 is a horizontal section taken on the line 2—2, in Fig. 1, the parts being shown on a much larger scale,

Fig. 3 is a perspective view of my improved device detached and with the emery wheel or grinding device proper removed.

The same reference characters indicate the same parts in all the views.

Let the numeral 5 designate the sewing machine considered in its entirety and of any ordinary construction, and 6 the fly-wheel thereof, which is operated in the usual manner, as by means of a belt connection, 17, with the motor or pedal-driving structure (not shown).

My improved device, as illustrated in the drawing, being one embodiment thereof, consists of a hollow, cone-shaped framework, 7, which is provided with a number of springs, 8, which are preferably secured to the inner surface of the hollow cone, as shown at 9, to which they may be brazed or soldered, or secured in any other suitable manner. These springs extend beyond the base or larger extremity of the cone and have their extremities bent outwardly, preferably as shown at 10, so that by moving them slightly inwardly they will pass through between the spokes of the fly-wheel, 6, and when released move outwardly into engagement with the rim of the wheel in such a manner as to maintain the device securely in place, causing it to rotate with the fly-wheel of the machine. The springs are so disposed as to engage the spokes of the fly-wheel, so that the frame structure must rotate therewith. One of the springs, 8, is preferably adjustable from the outside of the cone, being equipped with a pair of outwardly projecting loops, 12, which may be pressed inwardly, whereby the spring, 8, is adjusted to facilitate the attachment of the structure to the rim of the wheel. For instance, the other two springs, 8, may be placed in position on the wheel and then, by thrusting the third spring having the parts 12 inwardly and releasing it, the device will be firmly secured to rotate with the wheel.

The smaller extremity of the cone is open to receive the head, 13, of a stem, 14, which is secured to the smaller end of the cone in any suitable manner, whereby it is rigidly held in place. The part 13 has a shoulder which is engaged by the emery wheel or grinding member proper, 15, the latter being perforated to fit the stem 14, and being securely held thereon by means of a nut, 16, or in any other suitable manner, whereby the wheel 15 is readily detachable, as it may be.

110

come necessary to have a finer or coarser wheel at different times. Any suitable grinding material may be employed.

After the grinding member 15 is secured in place and the device attached to the fly-wheel of the machine, the latter may be operated to rotate the grinding attachment, in which event any articles may be ground or sharpened with great facility, as will be readily understood. Furthermore, by reason of the fact that the hollow, cone-shaped frame 7 is exteriorly closed, there is no opportunity for accident, as there would be if the device were open, since if it were open, a person might get his hand caught in the rotary structure, which might result in serious accident; hence the closed structure, preferably cone-shaped, is very important.

Having thus described my invention, what I claim is:

A sewing machine attachment, compris-

ing a hollow frusto conical frame whose larger extremity is adapted to fit snugly against the side of the fly wheel of a sewing machine, means on the inner face of said hollow frame at said larger extremity to project between the spokes of said fly wheel and engage said wheel to retain said frame thereon, said means comprising a plurality of elongated U-shaped resilient members having their inner ends secured to the inner side of said frame and their outer ends extending beyond said frame, one of said U-shaped members having an outwardly projecting portion (12) whereby the member may be readily operated for the purpose of attaching and releasing the frame from the wheel, an opening in said frame for receiving said projection and a grinding member mounted on the smaller end of said frame.

In testimony whereof I affix my signature.

LOOMIS N. McFALL.
